UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

WELL-SINKING APPARATUS.

1,343,902.

Specification of Letters Patent. Patented June 22, 1920.

Application filed June 10, 1918. Serial No. 239,295.

To all whom it may concern:

Be it known that I, MATTHEW T. CHAPMAN, a citizen of the United States, and a resident of Aurora, in the county of Kane and State of Illinois, have invented certain new and useful Improvements in Well-Sinking Apparatus, of which the following is a specification, reference being had to the accompanying drawings.

10 This invention relates to improvements in apparatus for sinking or boring holes in the earth to a considerable depth for the formation of wells for procuring water, oil, gas, &c., and has for one of its objects to provide an improved construction of drill tool that is peculiarly well adapted to utilize small and hard particles of material as an effective aid in the boring operation, such small hard particles of material being in some instances such as are broken from the hard strata through which the boring is being done, and in other instances being material dropped in from above for the express purpose of coöperating with the drill 15 to cut and grind away the bottom and sides of the hole. Another object of the invention is to so construct the drill tool that as it wears away in use such wear will be of a character that will tend to preserve a cutting edge even up to the time that the drill has been worn away by attrition so that it is but a small portion of its original length. These objects I accomplish as illustrated in the drawings and hereinafter particularly described. That which I believe to be new will be set forth in the claims.

In the drawings,—

Figure 1 is a view partly in side elevation and partly in vertical section of the mechanism for rotating the drill-carrying pipe, and showing also a side elevation of my improved drill at the bottom of a hole that has been formed by it;

Fig. 2 is a vertical central section through the drill shown in Fig. 1;

Fig. 3 is a bottom view of the drill.

Referring to the several figures of the drawings,—

10 indicates my improved drill which is adapted to be secured to the lower end of a line of boring pipe, such connection being effected in the construction shown by means of a coupling 11 that is screwed upon a neck 12 formed at the upper end of the drill and 55 also screwed to the lower end of the line of

boring pipe referred to—such boring pipe being indicated by 13. If deemed necessary, the coupling may be locked in place by any suitable means such as a key and slot in order to prevent disengagement of the parts 60 during the reverse rotation of the boring pipe, as hereinafter described. The drill is formed to provide two spiral flights, indicated respectively by 14 and 15, which are each formed with a comparatively wide vertically-disposed face adapted to present a broad bearing surface to the wall of the hole being formed. These spirals terminate at their lower ends, as clearly shown in Figs. 1 and 2, in flat horizontally-disposed faces 70 which results in the formation at such lower end of two sharp edge portions indicated by 16 and 17, such cutting edge portions being so directed that when the drill is rotating in boring direction, as indicated by the arrow on the boring pipe in Fig. 1, the loosened material from the bottom of the hole will be cut into and directed up over such sharpened edge portions and, with the water which is as usual forced under pressure 80 down through the boring pipe, will pass up the inclines afforded by the spiral flights 14 and 15. 18 indicates openings—quite a large number being shown—extending through each of the flights, said openings being, as 85 best shown in Fig. 2, inclined downwardly away from the outer walls of the flights. These openings 18 are provided for the purpose of receiving small particles of the hard gritty material which is broken off from 90 the hard layers or strata through which the drill progresses. Such fine hard particles will pass down these openings and lodge beneath the end of the boring tool or drill and be by such boring tool or drill further 95 crushed and rubbed around on the bottom, and thus grind away the bottom of the hole immediately behind the cutting edges of the tool. In the vertical outer sides of the spiral flights are formed a large number of slots 19, such slots being open at their ends and gradually tapering from their upper ends to the lower ends. The object of these slots is to receive small pieces of the hard gritty substances that are broken away during the boring operation and are carried up along with the water under pressure. The shape of these slots—larger at the top than at the bottom—facilitates the entrance at their tops of these small hard gritty pieces 110

and insures their retention in the slots. When so retained they serve as a grinding medium for rubbing and wearing away the wall of the hole being bored, and result in 5 such hole being made a little larger in diameter than the diameter of the drill, thus facilitating the more ready withdrawal of the drill when required for renewals or repairs, or when the boring operation is completed, and also preventing binding of the 10 drill in the hole while being rotated.

Formed longitudinally of the drill is a water passage 19^a adapted to conduct the water that is received under pressure from 15 the boring pipe 13. As shown this passage is made slightly eccentric with relation to the axis of the drill, and so making it is for the purpose of preventing the formation therein of a more or less solid core during 20 the boring operation which would interfere with or wholly prevent the desired passage of water. At intervals there are formed through the drill transverse passages, indicated by 19^b, which intersect the longitudinal 25 passage 19^a, these transverse passages being provided for permitting the water under pressure in the longitudinal passage 19^a to be forced out laterally to mix with and agitate the borings, and as it is desirable 30 to have such water emitted near the lower end of the drill I provide plugs such as 19^c for stopping up any desired number of the upper series of transverse openings 19^b. As the drill wears away these plugs 35 will be from time to time withdrawn so as to leave one or more openings for the discharge of water near the part that is then the bottom of the drill.

Referring now to the mechanism through 40 which the rotation of the boring pipe and its attached drill is effected, and the support for such mechanism,—20 indicates a frame of wooden beams as shown, or otherwise, upon which is supported a bed plate 21, 45 such bed plate in the construction shown having formed with it brackets 22 whose outer ends rest upon and are bolted to the framework 20. 23 indicates a large horizontally-disposed rotatable ring gear which 50 is secured upon the upper end of a short cylinder 24, which cylinder extends through a large opening in the bed plate 21. Between the ring 23 and the bed plate 21 are interposed a series of anti-friction bevel 55 rollers 25, such rollers projecting into suitable raceways formed in the lower and upper surfaces of the ring gear and bed plate, respectively. Secured upon the lower end of the cylinder 24 is another ring gear 60 indicated by 26, such latter ring gear being located below the bed plate. Both of the gears 23 and 26 are shown as being secured to the cylinder 24 by being screwed thereon, which is a convenient manner of attaching 65 them to the cylinder as it facilitates, of

course, the ready assembling of the parts in operative position. I have shown no means for locking these gears to the cylinder, but it will be understood that if found necessary or desirable they may be locked thereto in 70 any appropriate manner, as for example, in the manner suggested for locking the coupling 11 to either or both of the parts that it connects. The gear 23 is provided on its lower face with beveled teeth 27 and 75 the gear 26 has on its upper face a corresponding set of beveled teeth, indicated by 28, and with either of these teeth a driving pinion 29 is adapted to engage for producing the desired rotation of the boring pipe 80 and its attached drill. This bevel pinion 29 is fast on one end of a shaft 30, upon the other end of which is suitably secured a driving pulley, which, in the form of construction shown, is represented as a three- 85 step sprocket wheel 31 with any one of the sets of teeth of which a drive chain is adapted to engage so as to rotate the shaft at different speeds. Adjacent to the rear end of the shaft, by which is meant the end 90 farthest removed from the bevel pinion 29, such shaft passes through a bearing 32, from opposite sides of which bearing project trunnions 33 that are rotatably mounted in bearings 35 supported from the framework 95 20. 36 indicates collars fixedly secured to the shaft 30 at opposite ends of the bearing 32, which collars hold the shaft against endwise movement.

Any suitable means may be employed for 100 swinging the shaft 30 to bring the pinion 29 alternatively into engagement with either of the gears 23 and 26. In the construction shown I have provided for this purpose a rock-shaft 37 having slightly offset end 105 portions journaled in standards 39 rising from the frame 20. The rock-shaft 37 is connected with the shaft 30 by means of links 40 journaled at their upper ends on the rock-shaft and pivotally connected 110 at their lower ends with trunnions 42 extending laterally from a bearing 41 through which the shaft 30 passes. Upon a partial rotation of the shaft 37 by any suitable means about the axis defined by its offset portions, the shaft 30 is swung downward about the trunnions 33 serving to bring the pinion 29 into mesh with the gear 26 in lieu of the gear 23 as the parts are 115 shown in Fig. 1. The gear 23 is thus capable 120 of being driven in either direction as may be desired,—in one direction by direct contact with the pinion 29 and in the other direction through the medium of the cylinder 24 and the gear 26.

The boring pipe 13 is adapted to be driven in either direction as desired by the gear 23 by means of posts 48 rising therefrom and clamping mechanism 47 of any suitable type slidably mounted with respect 130

to said posts. In the construction shown, a brace-ring 49 is mounted on the upper end portions of said posts for holding the posts in parallel position with respect to each other.

In connection with the description of the construction and arrangement of the parts, the operation of the various features entering into this invention have been, to a considerable extent, described. Briefly summarized, however, it is as follows: A well sinking rig, such for example as set forth in Letters Patent No. 1,104,409, dated July 21, 1914, granted upon my application, will be set up in position provided with the usual means for raising and lowering the boring pipe and provided with means for supplying to such boring pipe a suitable supply of water under pressure. The parts being in the position shown in Fig. 1, a rotation of the drive shaft 30 will, as hereinbefore described, cause a rotation of the boring pipe and its attached drill, during all of which time water will be forced from a suitable source of supply through the boring pipe and drill. Some of the water passing down the passage 19^a of the drill will be forced out through the unstoppéréd transverse openings 19^b and will wash up and agitate the crushed material causing it to flow up the spiral flights with the water, and where the material being bored through is of a very hard, flinty, or gritty character many of the small particles thereof that are dislodged will enter the inclined openings 18 and work down through the successive flights and be brought beneath the bottom of the drill, and their action is such as to cause a continued grinding and disintegration of the material at the bottom of the hole with a result that the hole is rapidly made deeper, and, while a wearing effect is also produced on the material of the drill itself, such wearing has been found to be of a character that pre-serves in a large measure the sharpened cutting edges of the lowermost turns of the flights. In other words, the continued grinding effect of the comparatively small loosened hard particles between the bottom of the drill and the bottom of the hole acts to rapidly wear away the material through which the drill is progressing, and, while also acting, but, of course, in a very much slower manner, to wear away the drill itself, such wear on the drill is behind the acting or cutting edges 16—17 of the flights and hence cutting edges of the general character shown are effectively maintained throughout the life of the drill. Furthermore, the shape of the surface slots 19 is such that many particles of the very hard material that are broken off from the various strata are caught and held therein and serve as very effective abrading agents to contact and slightly but sufficiently wear away the

side wall of the hole, as hereinbefore described. The character of the various strata through which the drill or boring tool passes in the making of a deep well varies greatly, of course, and at times some of the strata will not afford the requisite amount of hard gritty material to serve as an abrading or cutting means beneath and around the drill. In such cases such needed elements can be supplied by dropping into the hole the requisite quantity of such material as, for example, granite chips, gravel, coarse sand, crushed stone, chilled shot or crushed steel particles—indeed, any small hard substance that can be carried around with the boring tool and that will serve the purpose of cutting and grinding away the bottom and sides of the hole.

In the operation of boring it will be found of advantage to turn the boring tool backward a few revolutions from time to time for forcing the borings beneath the drill so that they may be more readily crushed, rolled around and washed out and up, this being attained by the shifting of the shaft 30 as above described.

It will also be necessary from time to time to raise and lower the drill in order to properly force beneath the drill a quantity of the loosened hard particles of material to be rolled and crushed so as to serve as a proper abrading means, but I have not deemed it necessary to show such raising and lowering means. A construction for such purpose will be found fully illustrated and described in my said Letters Patent No. 1,104,409.

The invention has been described more particularly in connection with boring operations conducted through strata of very hard materials, but the apparatus will, of course, be equally effective in strata of different character and without the employment of much, if any, of the hard particles mentioned. I might also mention that when a stratum of material, such, for example, as tough clay, is encountered by the drill, the action of the water that is fed downward under pressure as described will be to so loosen or disintegrate it as to separate therefrom any small hard particles embedded therein and thus render such particles capable of being utilized as an abrading medium. If, however, such clay or other comparatively soft material is free from hard particles then the introduction of a quantity from above may be resorted to as an aid to the action of the drill.

The angle of the flights 14 and 15 may be varied within wide limits from that shown to better adapt the drill to differing conditions or to conform to the ideas of individual users.

The slots 19 may, if desired, extend only partly across the edges of the flights, being

180

in such cases preferably open at their upper ends.

So far as I am aware, I am the first in the art to provide a drill substantially in 5 the form of a cylindrical block grooved spirally in the manner above described, with the space between adjacent portions of the groove of substantially the same width vertically as that of the groove. Inasmuch as 10 this form of drill is very heavy and durable and may be produced readily by casting with very little machine work necessary for completing the drill, I consider this feature of my invention of very considerable importance. By making the spiral grooving of a 15 depth of approximately one-third of the diameter of the drill, ample clearance is afforded for the escape of the dirt and rock torn loose during the drilling operation 20 while at the same time the drill presents to the walls of the hole being bored such a surface and mass of metal as to be capable of long-continued use without replacement, particularly in view of the adaptability of 25 the device for carrying about with it the loosened particles of abrading material as is above described, such material being adapted to protect the drill and prevent undue wear.

30 While I have shown the slots 19 wedge-shaped for better holding the particles of abrading material in position on the face of the drill and prefer to employ this form, it will be understood that I do not limit 35 myself to the use of this particular form except as hereinafter specifically claimed, the provision of shoulders or ribs in the periphery by means of these slots being of importance for carrying the particles of abrading 40 material about with the drill whether or not the slots taper toward their lower ends.

What I claim as my invention and desire to secure by Letters Patent, is—

45 1. A rotary well-boring drill comprising a flight having means in its edge for receiving and retaining small hard particles so that they will project from such edge and act against and wear away the wall of the hole being bored.

50 2. A rotary well-boring drill comprising a flight having means in its edge for receiving and retaining small hard particles so that they will project from such edge and act against and wear away the wall of the hole being bored, in combination with means 55 for conducting water under pressure to the bottom of such hole whereby some of such hard substances as have been loosened by the action of the drill will be forced up the flight and caught and held by said retaining means.

60 3. A rotary well-boring drill comprising a flight having means in its edge for receiving and retaining small hard particles so that 65 they will project from such edge and act

against and wear away the wall of the hole being bored, the spiral being also provided with openings therethrough for conducting small particles of hard material below the drill to serve as an abrading means for wearing away the bottom of the hole. 70

4. A rotary well-boring drill comprising a flight having means in its edge for receiving and retaining small hard particles so that they will project from such edge and act against and wear away the wall of the hole being bored, the spiral being also provided with openings therethrough for conducting small particles of hard material below the drill to serve as an abrading means 75 80 for wearing away the bottom of the hole, each of said openings being inclined to direct the said particles back of the cutting edge of the drill.

5. A rotary well-boring drill comprising 85 a flight having means in its edge for receiving and retaining small hard particles so that they will project from such edge and act against and wear away the wall of the hole being bored, the spiral being also provided 90 with openings therethrough for conducting small particles of hard material below the drill to serve as an abrading means for wearing away the bottom of the hole, in combination with means for conducting water under pressure to the bottom of such hole, whereby hard substances that have been loosened by the action of the drill will be forced up the flight and some of the smaller particles thereof will enter said retaining means in the edge and other particles 95 will pass down through said openings.

6. A rotary well-boring drill comprising a flight having a plurality of wedge-shaped 100 slots in its edge for receiving and retaining small hard particles so that they will project from such edge and act against and wear away the wall of the hole being bored. 105

7. A rotary well-boring drill comprising a flight having a plurality of wedge-shaped 110 slots in its edge for receiving and retaining small hard particles so that they will project from such edge and act against and wear away the wall of the hole being bored, the flight being also provided with openings therethrough for conducting small particles of hard material below the drill to serve as an abrading means for wearing 115 away the bottom of the hole.

8. A rotary well-boring drill comprising 120 a flight having a plurality of wedge-shaped slots in its edge for receiving and retaining small hard particles so that they will project from such edge and act against and wear away the wall of the hole being bored, the flight being also provided with openings 125 therethrough for conducting small particles of hard material below the drill to serve as an abrading means for wearing away the bottom of the hole, each of said openings be- 130

ing inclined to direct the said particles back of the cutting edge of the drill.

9. A rotary well-boring drill comprising a flight having its lower face substantially at right angles to the axis of the drill whereby a cutting edge is formed on the lowermost turn of the flight, openings being provided through the flight for the passage of particles of hard material to the bottom of the hole being bored to serve as an abrading means beneath the drill.

10. A rotary well-boring drill comprising a flight having its lower face substantially at right angles to the axis of the drill whereby a cutting edge is formed on the lowermost turn of the flight, each turn of the flight being provided with one or more inclined openings therethrough to direct the passage of particles of hard material to the bottom of the hole being bored and in rear of the said cutting edge, whereby such material will serve as an abrading means beneath the drill.

11. A rotary well-boring drill comprising a flight having its lower face substantially at right angles to the axis of the drill whereby a cutting edge is formed on the lowermost turn of the flight, the flight having openings therethrough for directing particles of hard material to the bottom of the hole being bored to serve as an abrading means beneath the drill, and the flight having indentations in its edge for receiving and holding other particles of hard material that serve to abrade the wall of such hole.

12. A rotary well-boring drill comprising a flight having its lower face substantially at right angles to the axis of the drill whereby a cutting edge is formed on the lowermost turn of the flight, the flight having openings therethrough for directing particles of hard material to the bottom of the hole being bored to serve as an abrading means beneath the drill, and the flight having indentations in its edge for receiving and holding other particles of hard material that serve to abrade the wall of such hole, in combination with means for conducting water under pressure to the bottom of the hole to force the borings up the flight and carry small hard particles thereof to said openings and indentations.

13. A rotary well-boring drill comprising a flight the lower face of which has a substantially horizontal face whereby a cutting edge is formed on the lowermost turn of the flight and having the several turns of the flight formed with relatively wide edges that are substantially parallel with the axis of

the drill, such edges having indentations 60 therein that open at their ends into the spaces between the turns of the flight, in combination with means for conducting water under pressure to the bottom of the hole being bored to force the borings up the 65 flight and carry small hard particles thereof to said indentations, said particles forming an abrading means for wearing away the wall of said hole.

14. A rotary well-boring drill substantially in the form of a cylindrical block grooved spirally in its periphery, the space between adjacent groove portions being of substantially the same width vertically as that of the groove.

15. A rotary well-boring drill substantially in the form of a cylindrical block provided in its periphery with a plurality of spiral grooves of substantially the same width vertically as that of the space between 80 adjacent turns of said grooves.

16. A rotary well-boring drill substantially in the form of a cylindrical block grooved spirally on its periphery to a depth of approximately one-third of the diameter 85 of the drill, the space between adjacent groove portions being of substantially as great width vertically as that of the groove.

17. A rotary well-boring drill substantially in the form of cylindrical block grooved 90 spirally in its periphery, the space between adjacent groove portions being of substantially the same width vertically as that of the groove, and the periphery of the drill being provided with substantially vertically 95 disposed shoulders between adjacent groove portions for carrying about with the drill loosened particles of abrading material.

18. A rotary well-boring drill substantially in the form of a cylindrical block 100 grooved spirally in its periphery, the space between adjacent groove portions being of substantially the same width vertically as that of the groove, said drill being provided with a longitudinal conduit therethrough 105 and diagonally disposed openings from the groove to said conduit for conducting loosened particles of abrading material to the bottom of the hole being bored.

19. A rotary well-boring drill comprising a flight, the drill having a conduit extending longitudinally therethrough and opening at its lower end in eccentric position with respect to the axis of the flight, and also having laterally-directed passages 115 communicating with said conduit between the several turns of the flight.

MATTHEW T. CHAPMAN.
